SHIRT COLLAR CONSTRUCTION
William A. Frank, Jr., 3411 Alamo Ave.,

Cincinnati 9, Ohio

Continuation of application Ser. No. 217,309, Aug. 16,
1962. This application July 22, 1963, Ser. No. 296,780

5 Claims. (Cl. 2—141)

This invention relates to shirts and is particularly directed to a novel shirt collar construction including means for providing the collar with two distinctly different style configurations. This application is a continuation of my co-pending application Serial No. 217,309 for "Fastener for the Wings of Collars," now abandoned.

The principal object of the present invention is to provide a shirt collar which can be selectively worn in a "spread" style with the edges of the collar wings diverging along substantially straight lines or in a "tab" style in which the center portions of the edges of the collar are pinched together to tightly embrace the knot of the wearer's tie.

Another object of the present invention is to provide a simple tab element in combination with means for selectively mounting the tab element in an operative position in which it engages the mid point of both collar wings and draws them together to configure the collar in a tab style. Means are also provided for mounting the tab in a concealed position in which it is held beneath one of the collar wings when the collar is configured in a "spread" configuration.

More particularly, one preferred form of shirt collar constructed in accordance with the principles of the present invention comprises a generally conventional soft collar including two wings, the confronting edges of which normally diverge downwardly from one another at an angle. Each of the collar wings is provided on its undersurface with a fastener element, the fastener elements being disposed approximately midway between the upper edge of the collar and the wing tip. At least one wing of the collar is also provided with a second fastening device spaced from the first.

A fastening tab is used in conjunction with the collar. This tab in one preferred form comprises a thin elongated strip of semi-rigid plastic material, such as celluloid. Spaced inwardly a slight distance from each end of the tab are two fastening elements adapted to cooperate with the fastener elements mounted on the undersurface of the collar wings. The spacing of the fastener elements on the tab is appreciably less than the normal spacing of the fastener elements on the two wings when the collar is worn in its spread position. Consequently, when the tab is secured to the two wings, it is effective to draw or "pinch" the center portions of the wings inwardly to give the shirt collar a pinched or "tab" configuration. When the shirt is to be worn in the spread configuration, the tab is pivoted to a position in which both fasteners on one wing are engaged so that the tab is completely concealed. For laundering purposes, the tab can be completely removed from the shirt if desired.

One of the principal advantages of the present shirt collar construction is that it provides a simple means for quickly converting a shirt from one collar style to another, depending upon the wearer's desire for the particular social occasion at hand.

Another advantage of the present shirt collar construction is that when the shirt is worn in a tab style, the tab extends straight across the collar in a position in which it is hidden by the tie knot.

A still further advantage of the present invention is that the wearer can easily change the position of the tab while the shirt is being worn. More particularly, the provision of a semi-rigid tab in which an endwise portion of

2

the tab extends slightly beyond the fastener elements provides lips which can easily be gripped with a fingernail, or the like, to unsnap the tab. Also, the tab connection to the wing is a pivotal connection so that the tab can readily be pivoted to a position in which it is disposed under one wing.

Another advantage of the present tab construction is that it does not add appreciably to the cost of a conventional shirt collar. Moreover, the tab construction is durable and readily outlasts the normal life of the collar.

These and other objects and advantages of the present invention will be more readily apparent from a consideration of the following detailed description of the drawings illustrating a preferred embodiment of the invention.

In the drawings:

FIGURE 1 is a fragmentary front elevational view of a shirt collar provided with the fastener attachment of this invention, a four-in-hand tie being shown thereon in dotted lines.

FIGURE 2 is a fragmentary elevational view of the collar illustrated in FIGURE 1 with the collar in a turned up position.

FIGURE 3 is a greatly enlarged cross sectional view taken along line 3—3 of FIGURE 1.

FIGURE 4 is a plan view of a preferred form of collar fastening attachment.

FIGURE 5 is a view similar to FIGURE 1 showing the attachment of this invention in operative position connecting together the wings of a soft collar.

30 As is best shown in FIGURES 1, 2 and 5, one preferred form of shirt collar embodying the present invention comprises a generally conventional soft collar 8 sewed in the usual manner on a shirt 9. The soft collar includes a neck band 10 and a folded over outer band 11 terminating at its front in opposed wings 12 and 13. The wing fastening device of this invention consists of a detachable tab 14 removable, when desired, from the collar. Tab 14 is preferably made of a thin strip of plastic material, but alternatively may be composed of relatively stiff multiply fabric material, or the like. Each terminal end of the tab 14 is provided with the cooperating part 15 of a fastener, as for instance, the male element of a conventional separable, snap fastener device, this male element comprising clinched parts 16 and 17 (FIGURE 3) for securing the element to the tab. As is best shown in FIGURE 4, the ends of tab 14 extend outwardly for a short distance beyond the snap fastener parts.

As best shown in FIGURE 3, the folded over band 11 of the collar preferably has an outer ply 18 and an inner ply 19, and with respect to FIGURES 1 and 2, it will be noted that cooperating fastener parts 20, such as the female elements of the usual snap fastener device, are secured to the inside face of the inner ply 19 of the folded over band 11 in positions along the adjacent, confronting edges of the collar wings 12 and 13. These fastener parts 20 are positioned approximately midway between the tips of wings 13 and the upper edge of the collar.

The secured, inoperative position of the fastener tab 14 is determined by the position of a cooperating snap fastener element 21, also of the female type, located along the lower edge of at least one of the collar wings and removed rearwardly from the element 15 a distance identical to the spaced apart distance of the fastener elements 15—15 on the tab 14. In the drawing each collar wing 12 and 13 is shown as provided with a snap fastener element 21 but the invention could be practiced with but one element 21 if desired.

FIGURES 1 and 2 show the collar and tab when the collar is being worn as a "spread" style collar. When the collar is so worn, the edges of the collar are relatively straight and form a downwardly opening V. When the collar is worn in this position, tab 14 is pivoted about snap

fastener 20 to a rearward and upward position in which the fastener element 15 mounted on the free end of the tab is disposed to cooperatively engage the second element 21 mounted on the undersurface of collar wing 12. In this position the tab is completely hidden and since it lies flat against the undersurface of the collar wing it in no way impairs the appearance of the shirt.

When the collar is to be worn in a "tab" collar configuration as is shown in FIGURE 5, the fastener 15 on tab 14 is disengaged from cooperating fastener element 21. This disengagement can readily be effected by grasping the endwise portion of tab 14 which extends outwardly beyond the snap fastener elements 15 and 21. The tab member is rotated about cooperating fastener elements 15 and 20 until it extends horizontally between collar wings 12 and 13. It is to be understood that the spacing between snap fastener elements 15 on tab member 14 is substantially less than the normal spacing between cooperating snap fastener elements 20 on collar wings 12 and 13 when the collar is worn in its spread position as is shown in FIGURE 1. Thus, in order to secure the collar wings in the tab position shown in FIGURE 5, the mid points of the collar must be drawn together to bring the snap fastener element on the free end of the tab into registry with the cooperating snap fastener element of collar wing 13.

When the tab member 14 has been fastened to both collar wings, it extends horizontally beneath and is completely hidden by the knot of the wearer's tie, the knot being urged forwardly slightly so that it is tightly embraced by the collar wings. As is shown in FIGURE 5, the tips of the wings then diverge below the tab member 14. If desired for laundering or for some other purpose, the tab may be completely removed from the collar by disengaging both elements 15 of the tab from the cooperating fastener elements on the undersurface of the collar wings.

From the above disclosure of the general principles of the present invention and the above description of a preferred embodiment, those skilled in the art will readily comprehend various modifications to which the invention is susceptible. Accordingly, I desire to be limited only by the scope of the following claims.

Having described my invention, I claim:

1. A wing type shirt collar construction selectively configurable in a spread wing style or in a tab style, said collar comprising an upper edge and two downwardly diverging opposed wings, said wings having concealed undersurfaces, tips and confronting edges disposed along generally straight lines when the collar is worn in a spread wing style configuration, a tab member, first means securing one end of said tab member to the undersurface of one wing intermediate the upper edge and tip of said wing, said first means being effective to support said tab in an operative position in which said tab extends between said wings and in a reversed position in which said tab underlies said one wing, second means for releasably securing the opposite end of said tab member to the undersurface of the opposite wing intermediate the upper edge and tip of said opposite wing, the length of said tab being appreciably less than the spacing of said first and second fastening means when the collar is configurated in a spread condition, said tab when interconnected to said first and second fastening means being effective to configurate said collar wings in a tab configuration with the confronting edges of said wings pinched inwardly, and third fastening means mounted upon the undersurface of said first wing and spaced from said first fastening means to cooperatively engage said opposite end of said tab member when said tab is in its reversed position, said tab being supported in a flat condition under said first collar wing and being concealed when said collar is configurated in a wing style.

2. A wing type shirt collar construction selectively configurable in a spread wing style or in a tab style, said collar comprising an upper edge and two downwardly diverging

opposed wings, said wings having concealed undersurfaces, tips and confronting edges disposed along generally straight lines when the collar is worn in a spread wing style configuration, a tab member, first means securing one end of said tab member to the undersurface of one wing substantially half-way between the upper edge and tip of said wing, said first means being effective to support said tab in an operative position in which said tab extends between said wings and in a reversed position in which said tab underlies said one wing, second means for releasably securing the opposite end of said tab member to the undersurface of the opposite wing substantially half-way between the upper edge and the tip of said wing, the length of said tab being appreciably less than the spacing of said first and second fastening means when the collar is configurated in a spread condition, said tab when interconnected to said first and second fastening means being effective to configurate said collar wings in a tab configuration with the confronting edges of said wings pinched inwardly, and third fastening means mounted upon the undersurface of said first wing and spaced from said first fastening means to cooperatively engage said opposite end of said tab member when said tab is in its reversed position, said tab being supported in a flat condition under said first collar wing and being concealed when said collar is configurated in a wing style.

3. A wing type shirt collar construction selectively configurable in a spread wing style or in a tab style, said collar comprising an upper edge and two downwardly diverging opposed wings, said wings having concealed undersurfaces, tips and confronting edges disposed along generally straight lines when the collar is worn in a spread wing style configuration, a tab member, first means pivotally and detachably securing one end of said tab member to the undersurface of one wing intermediate the upper edge and tip of said wing, said first means being effective to support said tab in an operative position in which said tab extends between said wings and in a reversed position in which said tab underlies said one wing, second snap fastener means for releasably securing the opposite end of said tab member to the undersurface of the opposite wing, the length of said tab being appreciably less than the spacing of said first and second fastening means when the collar is configurated in a spread condition, said tab when interconnected to said first and second fastening means being effective to configurate said collar wings in a tab configuration with the confronting edges of said wings pinched inwardly, and third snap fastening means mounted upon the undersurface of said first wing and spaced from said first fastening means to cooperatively engage said opposite end of said tab member when said tab is in its reversed position, said tab being supported in a flat condition under said first collar wing and being concealed when said collar is configurated in a wing style.

4. A wing type shirt collar construction selectively configurable in a spread wing style or in a tab style, said collar comprising an upper edge and two downwardly diverging opposed wings, said wings having concealed undersurfaces, tips and confronting edges disposed along generally straight lines when the collar is worn in a spread wing style configuration, a tab member, snap fastener elements on opposite ends of said tab member, a first complementary snap fastener disposed on the undersurface of one wing intermediate the upper edge and tip of said wing, a second complementary snap fastener disposed on the undersurface of the opposite wing intermediate the upper edge and tip of said wing, the spacing of the snap fastener elements on said tab being appreciably less than the spacing of said first and second complementary snap fasteners when the collar is configurated in a spread condition, said tab when interconnected to said first and second complementary snap fasteners being effective to configurate said collar wings in a tab configuration with the confronting edges of said wings pinched inwardly, and a third complementary snap fastener mounted upon the undersurface of said first wing and spaced from said first fastening

means to cooperatively engage said opposite end of said tab member to support said tab in a flat concealed position under said first collar wing when said collar is configurated in a wing style.

5. A wing type shirt collar construction selectively configurable in a spread wing style or in a tab style, said collar comprising an upper edge and two downwardly diverging opposed wings, said wings having concealed undersurfaces, tips and confronting edges disposed along generally straight lines when the collar is worn in a spread wing style configuration, a semi-rigid plastic tab member, snap fastener elements adjacent to opposite ends of said tab member, the ends of said tab member extending outwardly beyond said fastener elements, a first complementary snap fastener disposed on the undersurface of one 15 wing intermediate the upper edge and tip of said wing, a second complementary snap fastener disposed on the undersurface of the opposite wing intermediate the upper edge and tip of said wing, the spacing of the snap fastener elements on said tab being appreciably less than the spac- 20

ing of said first and second complementary snap fasteners when the collar is configurated in a spread condition, said tab when interconnected to said first and second complementary snap fasteners being effective to configurate said collar wings in a tab configuration with the confronting edges of said wings pinched inwardly, and a third complementary snap fastener mounted upon the undersurface of said first wing and spaced from said first fastening means to cooperatively engage said opposite end of said tab member to support said tab in a flat concealed position under said first collar wing when said collar is configurated in a wing style.
